UNITED STATES PATENT OFFICE

2,341,196

PUMP

Ernest J. Svenson, Rockford, Ill., assignor, by
mesne assignments, to Odin Corporation, Chi-
cago, Ill., a corporation of Illinois

Original application March 30, 1936, Serial No.
71,754. Divided and this application January
22, 1941, Serial No. 375,500

21 Claims. (CL 103—174)

This invention relates to pumping mechanisms, and more particularly to pumps of the variable displacement type.

It is an object of the invention to provide a variable displacement pump having incorporated therein improved means for adjusting the pump displacement, which means is readily operable throughout a given range of displacement adjustment, and operable in any adjusted position to accurately and positively maintain the pumping mechanism at the desired setting.

More specifically stated, it is an object of the invention to provide an improved eccentric type adjustment for variable displacement pumps and the like, the eccentric adjustment mechanism being operable to accurately position and maintain the pump displacement in any desired position within a given range of pump displacement adjustment. In accordance with the invention, the eccentric adjustment means includes two relatively movable eccentric devices, adjustable from a position where their eccentricities mutually equalize each other, progressively to a position where the eccentricities are additive in function whereby to provide adjustment throughout a given desired range, means being also provided to positively lock the parts in any adjusted position.

A further object of the invention is to provide, in a variable displacement pump, two independently operable pump displacement adjustment means, at least one of which is adjustably operable during the operation of the pump. To this end the invention contemplates the provision of a first adjustment means adjustable to set the pump to any suitable normal or desired rate of displacement within the pumping range, and a second adjustment means operable while the pump is in operation to modify the pump displacement from such normal displacement to another desired displacement which, for example, may be zero displacement.

Another object of the invention is to provide pump adjustment means, operable while the pump is in operation, to change the pump displacement from one given setting to another desired setting; and further to provide automatically operable means for causing the adjustment means to operate or function at any desired time or times.

Still another object of the invention is to provide improved means for inserting a valve housing or assembly into a pump body in a tight and leak-proof manner.

Various additional objects, advantages and

features of the invention will be apparent from the following specification, when taken in connection with the accompanying drawings wherein in certain preferred embodiments of the invention are set forth for purposes of illustration.

In the drawings, wherein like reference numerals refer to like parts throughout:

Fig. 1 is a partial, elevational view of a machine tool structure including a pumping mechanism constructed in accordance with the principles of the invention;

Fig. 2 is a diagrammatic view of the hydraulic circuit for the structure of Fig. 1, and including the pumping mechanism of the invention;

Fig. 3 is a sectional view of the structure of Fig. 1, taken on the line 3—3 thereof and more particularly illustrating the pump structure;

Fig. 4 is a view of a pump structure similar to that illustrated in Fig. 3, but incorporating auxiliary mechanism, a second adjustment means, to vary the pump displacement;

Fig. 5 is a transverse, sectional view of the pump mechanism of Fig. 4, taken substantially along the line 5—5 thereof;

Fig. 6 is a transverse, sectional view of the pump mechanism of Fig. 4, but taken substantially along the line 6—6 thereof;

Fig. 7 is a perspective view of the control cam mechanism for the pump of Fig. 4, detached from the pump housing;

Fig. 8 discloses the manner in which the discharge side of the pump shown in Fig. 4 could be slightly modified so as to convert said pump into an injector mechanism adapted for use on Diesel motors;

Fig. 9 is an elevational view, shown partly in section, of mechanism for controlling the second adjustment means of the pump of Fig. 4, said view being taken substantially along the line 9—9 of Fig. 10; and

Fig. 10 is a front, elevational view of the displacement control device shown in Fig. 9, a portion of the housing thereof being broken away to disclose parts otherwise hidden.

In the drawings, the pump structure of the invention has been shown in association with a machine tool structure which it is adapted to operate and propel, as the pump, due to its accuracy and positive and accurate adjustment characteristics, is well adapted for machine tool work. It is to be understood, however, that the pump, and its adjustment mechanisms, may be adapted for various operations and uses. This application is a division of my copending application, Serial No. 71,754, filed March 30, 1936, now issued

as Patent No. 2,266,829, dated December 23, 1941, and entitled Metal working apparatus.

Referring more particularly to the drawings, and first to Figs. 1, 2 and 3 thereof, the machine tool structure disclosed comprises a machine tool head unit designated generally by the numeral 40 slidably mounted on ways 48, Fig. 1, carried by a main machine supporting frame or base 42, and adapted to carry a series of rotatable tool supporting spindles 112. A fluid motor indicated generally by the reference numeral 114, Figs. 1 and 2, and comprising a piston 118 and piston rod 120 secured to the main frame 42 and a cylinder 116 carried by the head frame unit 40 is provided for propelling the head frame along the ways 48. Pumping means such as a rapid traverse pump 134 and a plunger pump 136, Fig. 3, the latter pump forming the subject matter of the present invention, are provided in cooperation with suitable valve means, such as indicated by the reference numeral 208, Figs. 1 and 2, for controlling the delivery of fluid to the hydraulic motor 114.

The head frame 40 carries a suitable prime mover such as an electric motor 50, Fig. 1, for driving the tool spindles 112 and the pumps. To this end the electric motor 50 carries a pulley 54 adapted, by means of belts 66, to drive a pulley 62 carried by a main drive shaft 54. This drive shaft drives the spindles 112 and is also provided with a gear 88, Figs. 1 and 3, adapted to cooperate with and drive a gear 138 secured to a pump drive shaft 140, one end of which is adapted to drive the rapid traverse pump 134, and the other end of which is adapted to drive the plunger pump 136 forming the subject matter of this invention. Pump drive shaft 140 is carried by ball bearings 142 and 140.

Referring more particularly to the pump 136, its construction is in general similar to that disclosed in my copending application, Serial No. 684,677, filed August 11, 1933 and now issued as Patent No. 2,215,257, dated September 17, 1940. More specifically it consists of a pump body or housing 154 suitably secured to the head frame casting at 156, Fig. 3, as by means of screws (not shown). The pump 136 includes a suitable number of pistons 158, five in the present embodiment, and these pistons are reciprocably mounted within the pump body 154. I provide an inlet valve assembly 160 for each piston 158, and an outlet valve assembly 162 for each of said pistons, there being five inlet and five outlet assemblies in the embodiment shown. A unitary valve housing 164 is provided with seats for ball valve members 166 and 167, as clearly shown in Fig. 3. In manufacturing this structure, I found that pressing the unitary valve housing 164 into the pump housing 154 did not give satisfactory results, due to the shearing action of the pump body when the valve housing was being inserted. The absence of a tight fit presented the problem of fluid leakage. I therefore prefer to first subject the valve housing 164 to a shrinking process in "dry ice" or "liquid air," and if desired, also to subject pump body 154 to expansion in a heated body of oil. I then insert the shrunken or contracted valve housing 164 into the expanded pump housing 154, and when the temperature of said parts returns to normal a very tight leak-proof fit is obtained. I employ a bushing 168, which may be inserted within housing 164 by similar means, to seal an intake groove 170 communicating with the valves 166, an outlet groove

172 communicating with valves 167 being sealed by the pump 154.

In order to provide a variable eccentric or cam driving mechanism for the pistons 158 having a minimum number of parts, I prefer to eccentrically machine a stud or pin 174 directly on the pump variator drive shaft 140. A driving ring or bearing structure 176 includes an eccentric inner race member 178, which is mounted upon the eccentric crank pin 174. An outer race 188 and the ball bearings associated therewith are a commercial standard product, the only specially machined part being the inner race member 178. It will thus be apparent that by rotating the inner race member 178 with respect to the crank pin 174, a variation in piston stroke is obtained. To effect this relative rotation of the inner race 178 and the pin 174, I employ a sleeve 182 having a suitable coupling with the inner race 178, such as a pin and slot arrangement 184. A clamp stem 186 serves to support a clamping nut 188. To vary the stroke of the pistons 158, it is only necessary to remove a retainer cap 190, loosen the nut 188 slightly, and insert a suitable wrench so as to rotate the sleeve 182. By removing a cover plate 192 and a gasket 194, the entire pump housing 154 may be removed without disturbing the rotary driving elements, such as the eccentric driving pin and associated parts. For maintaining the pump variator drive shaft 140 in proper position, a retainer or ring 196 is employed, said retainer being secured in position by means of screws 198.

A detailed explanation of the functioning of the pump 136 is not necessary, and it will suffice to state that the pressure of fluid within the intake groove 170 opens each complementary ball valve 166 in turn, and causes the companion piston 158 to follow the movement of the eccentric driving mechanism 176. When said piston reaches the limit of its downward movement, said ball valve 166 closes and fluid is discharged under pressure as the piston is urged outwardly through its associated outlet valve 167. An auxiliary pump such as the pump indicated at 150, Fig. 3, or other suitable means, may be employed to maintain a suitable pressure in the intake groove 170.

The plunger pump 136, together with rapid traverse pump 134, is adapted to propel the fluid motor 114 through the control of the valve mechanism 208, as previously stated, the circuits being diagrammatically indicated in Fig. 2. However, inasmuch as the present invention more particularly concerns the pump structure, a detailed description of the valves, fluid circuits, and the like is believed to be here unnecessary. A full description of these mechanisms appears in my aforesaid application, Serial No. 71,754, of which the present application is a division.

As previously stated, my invention as applied to the pump 136 is not limited to a machine tool structure. For example, the driving arrangement and pump structure 136 is designed for application to Diesel motors or the like. In Fig. 3 I have disclosed the manner in which the outlet valve assembly 162 could be slightly modified by eliminating the groove 172 and providing a passage 204, which serves to direct fluid under pressure through a suitable channel or conduit 206, which may be connected with a cylinder of the Diesel motor (not shown). In other words, the ball valve mechanism just described may serve to properly inject fluid under pressure into any suitable device such as the cylinder of a con-

ventional motor employing fuel oil, for example, motors commonly known in the trade as Diesel type motors, and the timing of said injection will be governed by the disposition of the ball valves and the rotation of the eccentric driving mechanism 176. Obviously the number of pistons will conform with the number of cylinders or other devices into which fluid is to be injected.

One of the most difficult problems to solve in connection with the design of fluid control mechanisms such as hydraulic transmissions, where accuracy and variable displacement are required, is that of providing a practical, efficient control of the variable displacement of the pump. Many attempts have been made to solve this problem and, to my knowledge, none of these attempts has been wholly successful. In conventional hydraulic systems with which I am familiar positive coaction between elements designed to control pump displacement has not been obtained, and as a result the displacement control has not satisfied the demand in the industry for a simple, practical control arrangement. In fact, hydraulic controls should be designed with the idea of enabling even those unskilled in the art to understand the function of such controls.

I have previously explained the functioning of the simple eccentric driving mechanism 176 disclosed in Fig. 3, which includes the crank pin 174 and eccentric driving ring 178. That arrangement satisfies certain requirements in the field, but certain environments require further adjustment of the piston stroke. I accomplish this by incorporating within the pump housing 154 a simple cam device 468 (see particularly Figs. 4 to 7 inclusive). This cam device 468 includes an annular body portion 470 and a plurality of lateral cam elements 472 projecting laterally of the body 470.

These cam elements 472, which may be individually shaped to the adjustment requirements of each associated piston, are companion to pivoted pump fingers 474, which fingers are interposed between the inner ends of the pistons 158 and the periphery of the ring 180 of the eccentric driving mechanism 176. For a more detailed description and explanation of the pivoted fingers 474, reference is made to my copending application, Serial No. 548,569, filed July 3, 1931, and my Patent No. 1,989,118. When these cam elements 472 occupy the position shown in Figs. 4 to 6 inclusive, they serve to limit the inward movement of the fingers 474. In other words, the cam elements 472 serve to decrease the effective displacement of the pump. The cam structure 468 comprising the cam disc 470 may be rotated within limits determined by the adjustable stop member 498 (Figs. 9 and 10). Stop pins 476 carried by the pump housing maintain the cam disc 470 in position to be rotated, as shown in Figs. 4 and 6, while permitting the cam disc to be disassembled by matching the pins 476 with the slots 478 of the cam disc. The shifting of the cam mechanism 468 is accomplished by rotating a gear segment 482, which meshes with complementary teeth provided along the periphery of the cam body 470, said segment being mounted upon a shaft 484. By shifting the cam device 468, the effectiveness of the cam elements 472 upon the fingers 474 and consequently upon the pump pistons 158 may be varied. Thus when the cam elements 472 are shifted to the extreme position from that disclosed in Figs. 5 and 6, they do not engage the fingers 474 and permit the driving

mechanism 176 to function as previously described in connection with Fig. 3.

Obviously the limitation with respect to the range of stroke of the pistons 158, which is controlled by the cam elements 472, will vary in accordance with the environment in which the device is to be employed. I have found it practical to select a maximum normal displacement in accordance with the circumstances under which the pump is to be used by adjusting the eccentric driving mechanism 176 and to vary from said normal displacement to a minimum displacement requirement by interrupting the movement of the fingers 474, as above described. I have found that better results in the propulsion of a hydraulic actuator—for example, the actuator 114—are obtained when the displacement in the lower ranges is controlled by the cam mechanism 468. At extremely low displacement, or in other words, relatively short piston strokes, leakage is reduced to a minimum, and material or metal expansion is also obviated. It should be understood that the number of pistons employed controls the practical range of variation which may be accomplished by controlling the finger movements. I have found it practical to select a normal pump displacement of half the piston stroke by adjusting the driving mechanism 176, and to employ the finger or cam control mechanism to vary the displacement from this half stroke point to zero when five pistons are employed. Obviously if the number of pistons is changed, this will vary the range over which the cam or finger control may be used.

Any suitable means may be employed to adjust the cam mechanism 468, but referring to Figs. 9 and 10, it will be seen that I prefer to automatically shift the cam mechanism through the agency of a hydraulic actuator designated generally by the numeral 486. This actuator is supplied with fluid pressure through a passage 488 (Fig. 10), which pressure causes a piston 490 of the actuator 486 to shift to the left, the piston rod 492 of said actuator providing a rack which meshes with a gear segment 494. This gear segment 494 is mounted on the shaft 484, which also carries the gear segment 482. Therefore, shifting the piston 490 to the left (Fig. 10) causes the cam mechanism 468 to be adjusted. A spring 496 serves to shift the piston 490 to the right upon release of pressure within passage 488. An adjustable stop 498, which may be adjusted through the agency of a knurled head 500, serves to limit the forward movement of the piston 490.

A valve mechanism 502 serves to direct fluid to the actuator from a suitable source such as the circulating fluid of the rapid traverse pump 134. The valve 502 includes a valve piston 504, which carries an extension 506. This extension 506 is adapted to be operated by any suitable means, as for example by a dog 508 or the like suitably carried by the head frame 40 and adapted to engage the extension at a given point of movement of the head. A spring 510 urges the valve piston 504 outwardly, and a conduit or channel 512 at one extremity of the valve mechanism 502 connects with the channel 488. Fluid pressure is introduced to the valve through a port 514, which communicates with a longitudinal valve passage 516 and a cross channel or passage 518 when the valve member 504 is shifted to the left. Thus the shifting of the valve member 504 to the left in response to the engagement of the extension 506 with its operating means establishes communication of fluid under pres-

sure with the right extremity of the hydraulic actuator 486, and thereby causes the shifting of the piston 490 to the left. This shifting may be accomplished at any desirable point in the cycle of movement of the head. When valve 504 is permitted to return to the right, to the position of Fig. 10, valve passage 518 is brought into communication with a drain passage 519 whereby to relieve the pressure within channel 488 permitting spring 496 to act to return the piston 490.

From the foregoing it will be apparent that, when the eccentric driving mechanism 176 has been adjusted to cause the pump 136 to deliver fluid at a normal rate of displacement, the cam elements 472 are not engaged by the fingers 474. When a decrease in displacement is desired, which is determined by the position of the operating dog or the like for the extension 508, the valve member 504 is shifted to the left, which causes fluid to be delivered to the right end of the hydraulic actuator 486, thereby causing a shifting of the cam mechanism 468 and a consequent decrease in the fluid displacement of the pump.

Obviously numerous modifications and changes may be made without departing from the spirit and scope of the above described invention.

The invention is hereby claimed as follows:

1. A pump mechanism including a housing, shiftable pistons in said housing for receiving and discharging fluid, cam driving means for shifting said pistons, means including a member adapted to be functionally interposed between said cam driving means and said pistons for limiting the piston shifting effectiveness of said cam driving means, and means for shifting said member into interposed position.

2. A pump mechanism including a housing, shiftable pistons in said housing for receiving and discharging fluid, cam driving means for shifting said pistons, means including a cam member adapted to be functionally interposed between said cam driving means and said pistons for limiting the piston shifting effectiveness of said cam driving means, and means for shifting said cam member into interposed position.

3. A pump mechanism including a housing, shiftable pistons in said housing for receiving and discharging fluid, cam driving means for shifting said pistons, shiftable members between said cam driving means and said pistons, and adjustable stop means for limiting the movement of said shiftable members toward the axis of said cam driving means to limit the piston shifting effectiveness of said cam driving means.

4. A pump mechanism including a housing, shiftable pistons in said housing for receiving and discharging fluid, cam driving means for shifting said pistons, pivoted fingers between said cam driving means and said pistons, and adjustable stop means for limiting the movement of said pivoted fingers toward the axis of said cam driving means to limit the piston shifting effectiveness of said cam driving means.

5. A pump mechanism including a housing, shiftable pistons in said housing for receiving and discharging fluid, cam driving means for shifting said pistons, said cam driving means including an eccentric driving pin, an eccentrically apertured inner race member mounted on said pin, a concentrically apertured outer race member encircling said inner race member, shiftable members interposed between said outer race member and said pistons and bearing directly against said race member and said pistons, and means for relatively rotating said inner race

member and pin for purposes of cam adjustment, said shiftable members being pivotally mounted upon said housing.

6. Piston stroke controlling mechanism including an inner eccentrically apertured race member, an eccentric supporting pin therefor, an outer concentrically apertured race member encircling said inner race member, pivotal fingers engaging the outer race member, and means for relatively rotating said inner race member and pin for purposes of eccentric adjustment.

7. A pump mechanism comprising a housing, a shiftable piston associated with the housing for receiving and discharging fluid, cam driving means for shifting said piston, said cam driving means including an eccentric driving pin and an eccentrically formed ring member mounted on said pin, a member shiftable supported upon the housing interposed between the piston and the ring member, and means for relatively rotating said ring member and pin for purposes of cam adjustment.

8. Stroke controlling mechanism for shiftable elements and the like comprising a housing, an eccentrically apertured ring member in the housing adapted to shift the shiftable element, an eccentric supporting pin for the ring member, a member shiftable supported upon the housing interposed between the element and the ring member, and means for relatively rotating said pin and ring member for purposes of eccentric adjustment, whereby to vary the shifting movement imparted to said element.

9. Stroke controlling mechanism for shiftable elements and the like comprising cam driving means for shifting the shiftable element, adjustment means for varying the path of travel of the cam driving means whereby to vary the degree of shifting movement imparted to said element, and additional adjustable means functionally interposed between said adjustable cam driving means and said element for limiting the element shifting effectiveness of said cam driving means.

10. In a power driving mechanism including a member adapted to be reciprocated, driving means for reciprocating said member, adjustment means for the driving means to enable the driving means to reciprocate said member a selected distance of travel, and means associated with the driving means constructed and arranged to modify the limits of said distance of travel thereby imparting another and preselected travel of reciprocation to said member while maintaining said driving means in its adjusted position.

11. A pump mechanism including a housing, shiftable pistons in said housing for receiving and discharging fluid, eccentrically operable driving mechanism for shifting said pistons, means automatically operable during the operation of the pump for varying the piston shifting effectiveness of said driving means, and manual adjustment means for controlling the limits of operation of the automatic means.

12. A variable displacement pump including a housing, shiftable pistons in said housing for receiving and discharging fluid, driving mechanism for imparting varying amounts of shifting movement to said pistons, manual adjustment means for determining the maximum amount of movement imparted to the pistons by the driving means, manual adjustment means for determining the minimum amount of movement imparted to the pistons by the driving means, and means automatically operable during the operation of

the pump for varying the piston shifting effectiveness of the driving means between said manually predetermined limits.

13. A pump mechanism comprising a housing, shiftable pistons associated with the housing for receiving and discharging fluid, eccentrically operable driving means for shifting said pistons, said driving means including an eccentric driving pin and an eccentrically formed ring member mounted on said pin, and means for relatively rotating said ring member and pin to any position within their relative range of travel for purposes of eccentric adjustment, said last named means being arranged and adapted to rotate with the pin and ring member as a rotary unit during the operative functioning of the pump.

14. A pump mechanism including a housing, shiftable pistons associated therewith for receiving and discharging fluid, cam driving means for shifting said pistons, said driving means including an eccentrically disposed driving pin and an eccentrically formed ring member mounted on the pin, the amount of eccentricity of the pin and of the ring member being substantially equal, and adjustment means for relatively rotating the pin and ring member to any position within their relative range of travel for purposes of eccentric adjustment whereby the pin and ring member may be moved from a position wherein their eccentricities neutralize each other progressively to a position where the eccentricities are additive to produce a maximum cam throw, said adjustment means being arranged and adapted to rotate with the pin and ring member as a rotary unit during the operative functioning of the pump.

15. A pump mechanism including a housing, shiftable pistons associated with the housing for receiving and discharging fluid, cam driving means for shifting said pistons, means for limiting the movement of the pistons, and means for moving said limiting means selectively to an operative position for limiting the movement of the pistons, and to an inoperative position wherein the full piston shifting effectiveness of the cam driving means is transmitted to the pistons.

16. A pump mechanism including a housing, shiftable pistons associated with the housing for receiving and discharging fluid, cam driving means for shifting said pistons, means for limiting the movement of the pistons, and means for moving said limiting means selectively to an operatively position for limiting the movement of the pistons, and to an inoperative position wherein the full piston shifting effectiveness of the cam driving means is transmitted to the pistons, said means for moving the limiting means being operable during the operation of the pump.

17. A pump mechanism including a housing, shiftable pistons associated with the housing for receiving and discharging fluid, cam driving means for shifting said pistons, means for adjust-

ing the throw of the cam driving means, means for limiting the movement of the pistons, and means for moving said limiting means selectively to an operative position for limiting the movement of the pistons, and to an inoperative position wherein the full piston shifting effectiveness of the cam driving means is transmitted to the pistons.

18. A pump mechanism including a housing, shiftable pistons associated with the housing for receiving and discharging fluid, cam driving means for shifting said pistons, means for adjusting the throw of the cam driving means, means for limiting the movement of the pistons, and means for moving said limiting means selectively to an operative position for limiting the movement of the pistons, and to an inoperative position wherein the full piston shifting effectiveness of the cam driving means is transmitted to the pistons, said means for moving the limiting means being operable during the operation of the pump.

19. A pump mechanism including a housing, shiftable pistons associated with the housing for receiving and discharging fluid, cam driving means for shifting said pistons, means for limiting the movement of the pistons, means for moving said limiting means selectively to an operative position for limiting the movement of the pistons, and to an inoperative position wherein the full piston shifting effectiveness of the cam driving means is transmitted to the pistons, and means for adjusting the amount of limiting effectiveness of the limiting means when in operative position.

20. A pump mechanism including a housing, shiftable pistons associated with the housing for receiving and discharging fluid, cam driving means for shifting said pistons, means for adjusting the throw of the cam driving means, means for limiting the movement of the pistons, and means for moving said limiting means selectively to an operative position for limiting the movement of the pistons and to an inoperative position wherein the full movement of the cam driving means is transmitted to the pistons, and means for adjusting the amount of limiting effectiveness of the limiting means when in operative position.

21. A pump mechanism including a housing, shiftable pistons associated with the housing for receiving and discharging fluid, cam driving means for shifting said pistons, means for limiting the movement of the pistons, and fluid operable means operable while the pump is in operation for moving said limiting means selectively to an operative position for limiting the movement of the pistons, and to an inoperative position wherein the full piston shifting effectiveness of the cam driving means is transmitted to the pistons.

ERNEST J. SVENSON.
